UNITED STATES PATENT OFFICE.

JESSE DITSON, OF LITTLETON, COLORADO, ASSIGNOR TO INGERSOLL-RAND COMPANY,
OF JERSEY CITY, NEW JERSEY, A CORPORATION OF NEW JERSEY.

PIN-PULLER.

1,393,094.

Specification of Letters Patent. Patented Oct. 11, 1921.

Application filed July 6, 1920. Serial No. 394,246.

To all whom it may concern:

Be it known that I, JESSE DITSON, a citizen of the United States, residing at Littleton, in the county of Arapahoe and State of 5 Colorado, have invented a certain new and useful Improvement in Pin-Pullers, of which the following is a specification.

This invention relates to pin pullers and particularly to a device of this character arranged to operate in conjunction with a 10 drill sharpening machine to withdraw the pin from a hot drill steel, usually inserted into the bore of the steel to restore the bore to its proper diameter.

15 In present day mining drills, it is usual to provide the drill steel with a central hole extending throughout its length for the purpose of supplying air under pressure, and water, to the cutting edges of the bit to force 20 the debris away from the cutting edges and also to prevent overheating and the formation of dust. In resharpening a drill bit of the type above referred to, the metal is displaced, flowing and being forced into the 25 hole in the drill bit at every blow of the sharpening or forming tool and the hole thus soon becomes reduced or completely closed as the walls of the hole are closed in. It is customary to force a pin into the end of 30 the drill by any suitable means so that the pin penetrates into the hole and reopens the hole to its proper diameter. However, these pins frequently become tightly wedged in the hole, thus necessitating the use of a 35 pin puller to withdraw the pin. Such pin pullers have been provided either as separate machines or as an adjunct to the drill sharpening machine proper, operated independently either by hand or foot power or 40 by separate mechanical means.

The primary object of the present invention is to enable a pin puller to be conveniently mounted on a stationary portion of a 45 drill steel sharpening machine and operatively connected to a movable member of the drill sharpener, so that the pin puller is operated by said movable member of the drill sharpener, instead of by separate or independent manual means.

50 Further objects of the invention will hereinafter appear and to all of these ends the invention consists of the combination of elements and arrangement of parts substantially as hereinafter fully described in this 55 specification and shown in the accompanying drawings, in which,

Figure 1 is a side elevation partly broken away of a portion of a drill sharpener having the pin puller mounted thereon and operatively connected thereto;

60

Fig. 2 is an end view of the device, and Fig. 3 is a top plan view.

Referring to the drawings, A represents the base or cylinder of a drill sharpener having the vertically movable member or crosshead B carried by the plunger rod C adapted to be actuated by a piston (not shown) operating in the base or cylinder. The vertically movable member or crosshead B forms a suitable and convenient 65 means for imparting the required movements to the pin puller.

The pin puller shown in this instance comprises the frame D having the abutment E and adapted to be suitably secured to a stationary portion of the drill sharpener as by means of the bolts F. If desired, a depending arm G may be provided on the pin puller frame D and secured to a convenient portion of the drill sharpener in this instance 75 the arm G being secured over the exhaust pipe H.

The pin puller is provided with a horizontally movable jaw carrying member J adapted to slide in the guides K and L on the frame D. A gripping jaw O is fixedly carried by the jaw carrier J in this instance the jaw O being provided with a screw threaded stem P threaded into the end of jaw carrier J. Another coöperating jaw Q 90 is pivoted to a yoke R at S and said yoke is in turn pivoted to the jaw Q at T. The yoke R may be provided with a hook U at its lower end, adapted to be engaged by a rod V extending through guide lugs W. A 95 spring X surrounds the rod V and is adapted to be further compressed between lugs W and a stop pin Y at the end of the rod V when the jaw carrier J is moved toward the abutment E. As the jaw carrier J is 100 moved away from the abutment E the expansion of the spring X tends to rock the yoke R on the pivot T and clamp the jaws O and Q upon the pin a which is to be pulled from the drill steel b, abutting against the 105 abutment E, in this instance the bit end of a drill steel being shown in position against the abutment E. The abutment is preferably provided with a flared opening or recess j in which the end of the drill steel b 110 is adapted to rest and an aperture c joining the recess j into which the lower gripping

jaw O may extend as the jaw carrier J is moved toward the abutment. The limit of inward movement is reached when the yoke R lies flat against the abutment E. In such 5 position the jaws O and Q are at the maximum distance apart and the pin a extending through the central aperture d in the abutment E is free to pass between them and be gripped by the jaws as the jaw carrier is 10 moved away from the abutment.

In accordance with this invention, the jaw carrying member J is actuated toward and away from the abutment E by the movement of a movable member of the drill sharpener, 15 as for instance, the crosshead B. In order to operatively connect the jaw carrier J with the crosshead B an arm e is pivotally connected to the jaw carrier at f and removably attached at the other end to the crosshead B, as by means of the pin g carried by 20 the crosshead over which the recess H in the arm e is fitted. By this means the arm E may be disconnected from the crosshead when desired.

25 In the operation of the device the drill sharpener is actuated by motive fluid under pressure controlled by the usual throttle (not shown) and the movement of the crosshead B actuates the jaw carrier J toward and 30 away from the abutment E. As the jaw carrier moves away from the abutment E the pin a is gripped by the jaws O and Q and pulled out of the drill steel.

I claim:

35 1. A pin puller for pulling a pin from an object, adapted to be mounted on a stationary portion of a drill steel sharpening machine, said pin puller comprising a vertically movable crosshead forming part of 40 the drill sharpening machine, a stationary abutment, a jaw carrying member adapted to move toward and away from said abutment, a pin gripping jaw fixedly carried by said member, another pin gripping jaw 45 pivotally attached to said first mentioned jaw and means connected in operative relation with said crosshead of the drill sharpener for actuating said jaw carrying member toward and away from said abutment by the 50 movement of said crosshead, said means being adapted to be disconnected to render said pin puller inoperative.

55 2. A pin puller for pulling a pin from an object adapted to be mounted on a stationary portion of a drill steel sharpening machine, said pin puller comprising a vertically movable crosshead forming part of the drill sharpening machine, a stationary abutment, a jaw carrying member adapted to move 60 toward and away from said abutment, a pin gripping jaw fixedly carried by said member, another pin gripping jaw pivotally attached to said first named jaw, an arm pivoted to said jaw carrying member at one 65 end, the other end of said arm being de-

tachably connected to said crosshead of the drill sharpener, whereby said jaw carrying member is actuated toward and away from said abutment by the movement of said crosshead.

70 3. A pin puller for pulling a pin from an object, adapted to be mounted on a stationary portion of a drill steel sharpening machine, said pin puller comprising a vertically movable crosshead forming a part of the 75 drill sharpening machine, a stationary abutment, a jaw carrying member adapted to move toward and away from said abutment, pin gripping jaws carried by said member and operative means for actuating said jaw carrying member toward and away from 80 said abutment by the movement of said crosshead, said means comprising an arm pivoted to said jaw carrying member at one end, the other end being detachably connected to said crosshead and adapted to be disconnected to render the pin puller inoperative.

4. In combination with a drill sharpener 90 having a base and a movable crosshead, a pin puller frame mounted on said base, pin grasping means slidable in said frame, detachable means connecting said pin grasping means with the crosshead for actuating the pin grasping means to grip and 95 pull a pin when the crosshead moves in one direction, said pin grasping means being inoperative during movement of the crosshead when said connecting means are detached from the crosshead.

100 5. In combination with a drill sharpener having a base and a movable crosshead, a pin puller frame mounted on said base, a stationary abutment, gripping jaws carried on a member slidable in said frame, an arm pivoted to said jaw carrier and removably attached to said crosshead above said gripping jaws for moving said jaws away from 105 said abutment and simultaneously gripping and pulling a pin when said crosshead moves in one direction and moving said jaws toward said abutment when said crosshead moves in the other direction, said gripping jaws being idle when said arm is detached from said crosshead.

110 6. In combination with a drill sharpener having a base and a vertically movable crosshead, a pin puller frame rigidly mounted on said base, a stationary abutment, a gripping jaw holder horizontally slidable on said frame, gripping jaws mounted on said holder, an arm pivoted to said jaw holder and removably attached to said crosshead for moving said jaws away from said abutment and simultaneously gripping and pulling a pin when said crosshead moves in one direction, and toward said abutment when said crosshead moves in the other direction, said gripping jaws being idle 120 when said arm is detached from said cross- 125 holder.

head and swung on its pivot to a position below said jaws.

7. A pin puller for pulling a pin from an object adapted to be mounted on a stationary portion of a drill steel sharpening machine, said pin puller comprising a vertically movable crosshead forming part of a drill sharpening machine, an abutment for the said object, gripping jaws for gripping the pin and operative means detachably connected to the crosshead for causing relative movement between said abutment and jaws toward and away from each other by the movement of said crosshead, said means being adapted to be detached from the crosshead to render the pin puller inoperative during movement of the crosshead.

8. In combination with a drill sharpener having a base, a crosshead vertically movable in said base, a pin puller frame rigidly mounted on said base, said pin puller comprising a stationary abutment, a jaw carrying member adapted to move toward and away from said abutment, pin gripping jaws carried by said member, an arm pivoted to said jaw carrying member at one end, the other end of said arm being adapted to be detachably connected to said vertically movable crosshead whereby said jaw carrying member is actuated toward said abutment by the movement of said crosshead in one direction and away from said abutment by movement of said crosshead in the opposite direction, said jaw members being idle during movement of the crosshead when the arm is disconnected from the crosshead.

9. A pin puller for pulling a pin from an object adapted to be mounted on a drill steel sharpening machine, said pin puller comprising a stationary abutment, a jaw carrying member adapted to move toward and away from said abutment, a pin gripping jaw fixedly carried by said member, a yoke pivoted to said fixedly carried jaw, another pin gripping jaw pivotally attached to said yoke, constantly acting means en-

gaging said yoke for rocking it on its pivot to clamp said jaws on the pin, and a single separate means for actuating said jaw carrying member toward and away from said abutment.

10. A pin puller for pulling a pin from an object adapted to be mounted on a stationary portion of a drill steel sharpening machine, said drill steel sharpening machine having a vertically movable crosshead, said pin puller comprising a stationary abutment, a jaw-carrying member adapted to move toward and away from said abutment, a pin gripping jaw fixedly carried by said member, a yoke pivoted to said fixedly carried jaw, another pin gripping jaw pivotally attached to said yoke, means engaging said yoke for rocking it on its pivot to clamp said jaws on the pin, an arm pivoted to said jaw carrying member at one end, the other end of said arm being adapted to be detachably connected to said vertically movable crosshead, whereby said jaw carrying member is actuated toward and away from said abutment by movement of said crosshead.

11. In a pin puller for pulling a pin from an object adapted to be mounted on a stationary portion of a drill sharpening machine, said drill sharpening machine having a movable crosshead, a stationary abutment against which a drill steel is adapted to rest, clamping means comprising horizontally movable clamping jaws adapted to securely grasp a pin and means operated by the crosshead of the drill sharpening machine and engaging said clamping means for moving said clamping means toward and away from said abutment, said means being adapted to be withdrawn from operative engagement with said crosshead to render said clamping means inoperative during movement of the crosshead.

In testimony whereof I have signed this specification.

JESSE DITSON.
